WASTE SHAKER

William T. Bissell and Herschel H. Harold, Indianapolis, Ind., assignors to Journal Box Servicing Corporation, Indianapolis, Ind., a corporation of Indiana

Application June 3, 1940, Serial No. 338,534

7 Claims. (Cl. 19—81)

This invention relates to the art of reclaiming used journal box waste as illustrated by the U. S. Letters Patent No. 2,090,260, issued August 17, 1937, to applicant and others on a Process of reconditioning used waste. In any process of reclaiming used journal box waste, it is a common procedure to first initially loosen up the waste in hot oil, remove the wash oil by some compressing action such as by centrifugal action, a press, or the like, and then re-oil the waste with usable lubricating oil. During the reconditioning or reclaiming of the used waste, it becomes necessary at some step to loosen and fluff the waste so as to restore it to a resilient condition as opposed to the matted compressed condition it has reached when removed from the journal box.

It is a primary object of the present invention to provide structural means that will shake out and fluff the waste in a very effective manner without tumbling it and rolling it over and over, following an initial soaking or washing of the waste with hot oil. When the waste leaves the centrifuge or the press, the waste is quite compacted and it is the purpose of this invention to eliminate this compacted condition.

A further primary object of the invention is to provide such structural means as above indicated which will permit a continuous operation without intermittent stops and which will not only loosen the waste from its compacted condition but will also tend to shake out foreign matter as well as undesired short ends if such be present.

A further important object of the invention is to provide an exceedingly simple mechanism which will operate without requiring air blasts or any mechanical means tending to roll the waste, but instead operate much as a pitch fork is employed in shaking loose baled straw and the like on the farm.

These and many other objects and advantages of the invention will become apparent to those versed in the art in the following description of one particular form of the invention as illustrated in the accompanying drawings, in which

Fig. 1 is a side elevation of the central fragmentary part of the washing mechanism, as illustrated more fully in the U. S. Patent No. 2,090,260, to which the present invention is applied;

Fig. 2, a detail in side elevation of the shaker mechanism;

Fig. 3, a top plan view;

Fig. 4, a side view in perspective of the shaker; and

Fig. 5, a diagrammatic representation of the action of the shaker mechanism on the waste.

Like characters of reference indicate like parts throughout the several views in the drawings.

5 It is to be understood that while reference is made to the process of reconditioning used waste described in the U. S. Letters Patent No. 2,090,260, such process and the apparatus shown in that patent are referred to simply as one particular process to which the present invention may be adapted. In that process, there is a conveyer 10 which is continuously pulling waste up an inclined platform 11 from a wash tank (not shown). From the discharge end of the platform 11, the waste drops into the hopper 12 on the upper side of a press 13 corresponding in detail to the press shown in said Patent No. 2,090,260, the details of which press do not enter into the present invention. The press is referred to simply as one means of compressing the soaked or washed waste to remove the excess or principally all of the rinse or wash oil from the waste, the waste being discharged from the press 13 in a very compacted condition with only a firm coating of oil remaining on the waste fibers. As indicated in Fig. 3, two of these presses 13 are employed, one beside the other.

20 The discharging waste from these presses 13 is caught upon a series of fingers 14, herein shown as being directed away from the underside of the discharge openings of the presses 13 in substantially horizontal directions and in a common plane. Rear ends of these fingers 14 are secured in any suitable manner, such as by welding to a transverse bar 15 that is carried by the upwardly extending arms 16 and 17.

25 The upper ends of these arms are carried by crank pins 18 and 19 respectively projecting in the present forms from discs 20 and 21 rigidly mounted on a transverse shaft 22 above the presses 13. The arms 16 and 17 are thus simultaneously reciprocated upon turning of the shaft 22 so that the fingers 14 are raised and lowered in unison, as indicated in going from the solid lines to the dash lines in Fig. 2. In order to prevent the arms 16 and 17 from swinging rearwardly when the weight of the waste is on the fingers 14, pins 23 and 24 are respectively positioned behind the arms 16 and 17 to extend from the sides of the respective presses 13. As indicated, the forward terminal ends of the fingers 14 are preferably sharpened and turned slightly upwardly.

30 The forward ends of the fingers 14 in the present structure shown are positioned above a sec-

ond wash tank 25 over which a plurality of picker rods 26 are reciprocated in fore and aft directions as well as being intermittently raised and lowered to convey waste through the wash tank 25, all in the manner as shown and described in said Patent No. 2,090,260. Immediately under the fingers 14 is placed a platform 27, herein shown as being inclined rearwardly and downwardly under the presses 13. The forward end of the platform 27 terminates a substantial distance back of the forward terminal ends of the fingers 14 as indicated in Figs. 1 and 3.

As the compacted waste is pushed out of the presses 13, this waste will be extruded therefrom in a solid mass until the weight thereof breaks off sections in the nature of rectilinear cakes several inches thick in most instances. These cake-like formations of the pressed waste drop onto the fingers 14 between side arms 30 and 31 which are respectively fixed to the arms 16 and 17, and which are spring-like in nature. The fingers 14 are constantly being raised and lowered as indicated in Fig. 2, this action being sufficiently rapid to shake these matted cakes of waste up and down on the fingers 14 to further divide the cake into smaller masses and eventually loosen the waste fibers to separate them one from another very effectively. As the waste is extruded from the presses (a rather slow travel), this extruding waste tends to push off the loosened waste from the fingers 14 to allow that loosened waste to drop down from the forward terminal ends of the fingers 14. Fingers 30 and 31 aid not only in preventing the waste from falling off the fingers 14 sidewise, but tend to prevent masses of waste falling ahead over the ends of the fingers 14 before sufficient shaking.

As this loosened waste drops from these fingers 14, it will become impaled over the ends of these fingers and as the fingers continue to reciprocate, the waste is thus further loosened up and pulled apart quite effectively. This action is further accelerated and carried out to a greater degree when the waste strikes the body of oil 28 in the tank 25 where the oil absorbed and coating the lower end of the hanging waste will apply some additional weight to the waste and thus tend to hold the lower part of the waste down while the upper part is lifted and shaken quite effectively by those moving fingers 14.

Then as indicated in Fig. 5, the moving picker rods 26 will engage by their rear row into the loosened up waste directly under the forward ends of the fingers 14 and progressively pull and move that waste forwardly in the oil 28, further aiding in the separating and loosening of the waste fibers one from the other.

As above indicated, it is immaterial as to how the waste has been initially compacted, whether by the presses 13 or by a centrifuge. Where the centrifuge is employed, the waste, of course, must be removed by hand and in that case is dropped immediately on the shaker fingers 14 to be loosened up. In any event the rapid vertical reciprocatory action of the fingers 14 bounces the waste up and down on those fingers and over the terminal ends thereof to such an extent that the waste is fluffed up much more effectively than can be done by hand and at the same time there is no over-rolling action that would tend to form the waste into rolls as is sometimes the case where the waste is attempted to be tumbled following a compacting operation. While this reciprocating action is going on, any foreign material which has by chance not been removed

before the waste is compacted is effectively shaken out and caught on the platform 27. Also short ends that have not previously been removed will be shaken out and also caught on the platform 27. As may be noted, the forward ends of the fingers 14 are given a slight fore and aft movement by reason of the rocking of the arms 16 and 17 about the abutting pins 23 and 24 by reason of the upper ends of those arms having to follow the circle of travel of their connected crank pins 18 and 19. This slight fore and aft travel further aids in the action of fluffing up the waste and in its discharge from the fingers.

While we have herein shown and described our invention in the one particular form, it is obvious that structural changes may be employed without departing from the spirit of the invention and we, therefore, do not desire to be limited to that precise form beyond the limitations as may be imposed by the following claims.

We claim:

1. In a journal box waste reclaiming apparatus, the combination of a platform of spaced apart rod-like members each being independently free at one end of the platform, a pair of arms supporting the platform largely forwardly thereof, members back of said arms against which said arms may swing, and crank means to which said arms are connected to give said arms an up and down reciprocatory motion in sliding travel over said members, whereby said fingers have imparted to them a slight fore and aft travel.

2. For shaking out a mass of compacted waste, a plurality of spaced apart fingers onto which said waste falls; support means maintaining said fingers in substantial parallel alignment and from which said fingers extend by free ends; means for suspending said support means; means for vertically reciprocating said support means; and fulcrum means against which said support means bears by reason of the weight of said waste on said fingers tending to swing the fingers and their supporting means thereagainst, said fulcrum being below said suspending means and above said fingers against which fulcrum means said supporting means bears by reason of the weight of said waste on said fingers.

3. For shaking out a mass of compacted waste, a plurality of spaced apart fingers onto which said waste falls; support means maintaining said fingers in substantial parallel alignment and from which said fingers extend by free ends; means for suspending said support means; means for vertically reciprocating said support means; and fulcrum means against which said support means bears by reason of the weight of said waste on said fingers tending to swing the fingers and their supporting means thereagainst; said fulcrum being below said suspending means and above said fingers; and suspending means comprising a crank pin to which said support means is rockably fixed; and said reciprocating means revolving said pin in a continuous direction about a horizontal axis to impart a fore and aft longitudinal travel below said fulcrum to said fingers.

4. For shaking out a mass of compacted waste, a plurality of spaced apart fingers onto which said waste falls; support means maintaining said fingers in substantial parallel alignment and from which said fingers extend by free ends; means for suspending said support means; means for vertically reciprocating said support means; and fulcrum means against which said support means bears by reason of the weight of said waste

on said fingers tending to swing the fingers and their supporting means thereagainst; and means tending to retard movement of said waste mass over said fingers until said mass is sufficiently broken up by the finger reciprocation to allow the waste to escape over the free ends in smaller masses.

5. For shaking out a mass of compacted waste, a plurality of spaced apart fingers onto which said waste falls; support means maintaining said fingers in substantial parallel alignment and from which said fingers extend by free ends; means for suspending said support means; means for vertically reciprocating said support means; and fulcrum means against which said support means bears by reason of the weight of said waste on said fingers tending to swing the fingers and their supporting means thereagainst; and means tending to retard movement of said waste mass over said fingers until said mass is sufficiently broken up by the finger reciprocation to allow the waste to escape over the free ends in smaller masses; said waste retaining means comprising a spring member extending in the direction of said fingers from each side of said supporting means and inwardly laterally of the fingers and aided

10 by said fingers being confined to rocking in said fore and aft travel from substantially horizontal positions and thereabove to lift the free ends of the fingers.

6. For shaking out a mass of compacted waste, a plurality of spaced apart fingers onto which said waste falls; support means maintaining said fingers in substantial parallel alignment and from which said fingers extend by free ends; means for suspending said support means; means for vertically reciprocating said support means; and fulcrum means against which said support means bears by reason of the weight of said waste on said fingers tending to swing the fingers and

15 their supporting means thereagainst; and means tending to retard movement of said waste mass over said fingers until said mass is sufficiently broken up by the finger reciprocation to allow the waste to escape over the free ends in smaller masses; said waste retaining means comprising a spring member extending in the direction of said fingers from each side of said supporting means and inwardly laterally of the fingers and aided

20 by said fingers being confined to rocking in said fore and aft travel from substantially horizontal positions and thereabove to lift the free ends of the fingers.

7. For shaking out a mass of compacted waste, a plurality of spaced apart fingers onto which said waste falls; support means maintaining said fingers in substantial parallel alignment and from which said fingers extend by free ends; means for suspending said support means; means for vertically reciprocating said support means; and fulcrum means against which said support means bears by reason of the weight of said waste on said fingers tending to swing the fingers and their supporting means thereagainst; said fulcrum being below said suspending means and above said fingers; said suspending means comprising a crank pin to which said support means is rockably fixed; and said reciprocating means revolving said pin in a continuous direction about a horizontal axis to impart a fore and aft longitudinal travel below said fulcrum to said fingers; and means engaging parts of said waste as it falls from the free ends of said fingers whereby the engaged waste may be held long enough to be shaken while hanging free into loose strings.
